Invictor

S. F. Howk,

By Clarence A. O'Brien, Attorney

UNITED STATES PATENT OFFICE

SYLVESTER F. HOWK, OF SAN ANTONIO, TEXAS

ADJUSTABLE ELECTRIC RECEPTACLE

Application filed July 25, 1928. Serial No. 295,312.

The present invention relates to improvements in the art of electrical conductors and the same has specific reference to a novel mounting for electric receptacles wherein the receptacle is capable of being moved to remote points to accommodate electrical appliances without the necessity of employing conductor cords of considerable length.

The invention is also embodied in the combination with a metallic baseboard structure which customarily forms the lower portions of walls in lieu of the present board which is susceptible to quick damage.

The invention briefly consists in providing a hollow baseboard structure wherein a current conductive track is arranged, the front wall of the baseboard structure being formed with the longitudinally extending slot to permit a collector operable on the track to project through the said slot whereby connection may be had therefrom to electrical appliances.

The prime object of the invention resides in the provision of a combination baseboard and electrical receptacle mounting wherein the receptacle may be adjusted to any point on the walls of a room to accommodate electrical appliances rather than to encumber the appearance of the room by the employment of elongated conductor cords.

Another important object of the invention is accomplished by reason of the novel structural details involved in the baseboard construction wherein the conductor track will be guarded against accidental contact by a person and which will further present a durable and neat appearing structure far more appreciable than a conventional structure.

Other important objects of the invention reside in the means whereby the receptacle unit may be attached to the collector, brace means between the front and rear walls of the baseboard and novel means for mounting the

collector for movement on the conductor track.

In the drawings:

Figure 1 fragmentarily represents the side wall of the room provided with the novel baseboard structure, and further showing an electric receptacle properly mounted in association therewith,

Figure 2 is a vertical sectional view through a portion of the wall construction and transversely through the novel baseboard showing the particular manner of mounting the collector within the baseboard,

Figure 3 is an enlarged front side elevation of the collector,

Figure 4 is an enlarged rear side elevation of the collector, and

Figure 5 is an enlarged fragmentary sectional view through the collector and the electric receptacle connected therewith.

Referring to the drawings wherein like numerals designate like parts the conventional wall construction consists of studding A against which the usual metallic lathing B is secured.

As is customary in the construction of walls, the lower edge of the lathing B terminates at a point upwardly from the flooring C to permit space for the disposition of a baseboard.

In the present invention the baseboard includes a rear wall 1 provided with an outwardly disposed flange 2 at its upper edge.

This flange is preferably curved transversely and bent downwardly at its outer edge 3. This curvature of the flange 2 serves to assist the lathing B in supporting the plaster D applied thereto.

The lower longitudinal edge portion of the rear wall is also disposed outwardly and against the flooring B in the manner clearly shown in Figure 2. The longitudinal intermediate portion of the rear wall is disposed outwardly to provide upper and lower shoulders 4 and 5 respectively.

The inwardly disposed corrugations 6 on the shoulder form longitudinally extending channels in which insulating material 7 is deposited. It is to be understood that the rear wall as well as the front wall which will be fully described hereinafter may extend continuously on the walls of a room or may on the other hand extend for predetermined stretches, which in each case, is a matter of choice and has no effect on the scope of the present invention.

Elongated strips of current conducting material 8 are anchored at one of their longitudinal edge portions within the insulating deposit 7. In this manner the opposite longitudinal edges of the strip 8 project beyond the shoulders 4 and 5 respectively.

The front wall of the baseboard structure consists of an upper and a lower section 9 and 10 respectively. The lower edge portion of the lower section 10 is provided with a flange 11 which overlaps the lower flange of the rear wall 1 at its edge portion. The brace member 12 is interposed between the rear wall 1 and the upper section 9 of the front wall at suitable spaced intervals throughout their length.

The brace 12 is preferably connected permanently to the rear wall as at 13, while a set screw 14 permits the detachable connection of the upper section 9 to the outer end of the brace. The upper edge portion of the section 9 is curved for snug engagement with the curved edge portion 3 of the rear wall 1 flange 2.

By so mounting the upper section, the lower edge thereof will be spaced vertically on the upper edge of the lower section 10. The lower section 10 is also connected to the rear wall 1 by a brace 15, which brace is permanently connected to the rear wall at 16, while a set screw 17 permits the detachable connection of the lower section 10 to the outer end of the brace. Nails 18 may be driven through the respective walls at suitable points maintaining the same in contact with the studding A and the flooring C.

The current collector consists in the construction of an elongated block 19 of insulating material formed at its front side with a protuberance 20 adapted to project between the opposing edges of the respective upper and lower sections. Each end of the block 19 is provided with a rearwardly projecting pintle 21 on which a grooved roller 22 is mounted.

These rollers 22 are adapted to engage the conductor strip 8 in the manner clearly shown in Figure 2 for supporting the block 19 in a substantially vertical position. Positive and negative conductor members 23-23 project beyond the front face of the protuberance 20 and are each connected to the pintles 21 by conductors 24 trained through bores in the block 19.

A nut 25 is anchored within the protuber-

ance 20 between the conductor strip 23-23, and a bore 26 registers with the threaded opening therein.

An electric receptacle forming part of the present invention consists in the construction of a knob of insulating material 27 formed centrally with a bore 28 therethrough and being reduced toward one end, whereby a screw 29 may be inserted therethrough and engaged with the anchored nut 25 within the collector 75 19 for tightly securing the knob 27 thereto.

The knob 27 is also formed with a pair of spaced openings 30-30 in which spring contact clips 31 are arranged. The inner side of the knob 27 is formed with suitable openings to permit the insertion of the projecting end portions of the conductor strips 23-23 in the manner shown in Figure 5.

Set screws 32-32 are threaded inwardly on the knob 27 from diametrically opposite points thereof for connecting the strip 23-23 with the clip 31.

It will thus be seen that the collector and receptacle may be shifted to the desired point within the room and adjacent to the appliance to be energized. The short cord may be employed for connecting the receptacle to the appliance instead of the customarily long unsightly cord which has a very displeasing effect on the decorative appearance of the room.

It is also to be understood that certain changes in the specific shape, size and materials employed in the construction of this invention may be resorted to without departing from the spirit of the invention or the scope of the appended claims.

Having thus described my invention, what I claim as new is:

1. An electrical outlet comprising an elongated housing, said elongated housing including a front and rear section, said front section being provided with a slot means for detachably connecting the front section to said rear section, said rear section being de- 110 formed to provide a longitudinal trough, an insulated body disposed within the trough, and a longitudinally extending conductor track mounted upon the body, and a current collector movable in the slot on the front section to ride on the said conductor.

2. An electrical outlet comprising an elongated housing, said elongated housing including a front and rear section, said front section being provided with a slot means for detachably connecting the front section to said rear section, said rear section being formed to provide a longitudinal trough, an insulated body disposed within the trough, and a longitudinally extending conductor track mounted upon the body, and having a portion thereof anchored in said body, and a current collector movable in the slot on the front section to ride on the said conductor.

3. An electrical outlet comprising an elong-

gated housing, elongated housing including a front and rear section, said front section being provided with a slot means for detachably connecting the front section to said rear section, said rear section being formed to provide a longitudinal trough, an insulated body disposed within the trough, and a longitudinally extending conductor track mounted upon the body, and having a portion thereof anchored in said body, and a collector 10 slidable on said tracks, and along the slots in the front section.

In testimony whereof I affix my signature.
SYLVESTER F. HOWK.
